TENNIS BALL HOLDER

William C. Kinard, 3710 Alder Lane,
Pasadena, Calif. 91107

Filed Nov. 3, 1972, Ser. No. 303,638

Term of patent 14 years

Int. Cl. D21—02

U.S. Cl. D34—5 ST

Fig. 1

Fig. 3

FIG. 1 is a front view of a tennis ball holder formed of round wire showing my new design;

FIG. 2 is a top view of the tennis ball holder; and

FIG. 3 is a side view of one of the two identical sides of the tennis ball holder.

I claim:

The ornamental design for a tennis ball holder, substantially as shown and described.
